UNITED STATES PATENT OFFICE.

FRANK BOGASKIE, OF JOHNSTOWN, NEW YORK.

SELF-RIGHTING STAMP.

Application filed April 16, 1927. Serial No. 184,317.

My invention relates to stamps of the general character known as "rubber stamps" and particularly to a means forming a part of or adapted for attachment thereto whereby the stamp, when dropped or laid upon a flat surface, will always arrange itself in a predetermined position.

When a person is about to use a rubber stamp it is first necessary for him to ascertain whether the type in the stamp are arranged so that the impression on the paper will be "right side up". This may be done by examining the type but it is usual to have a mark or indication upon one side of the stamp which if held toward the operator will insure that the impression be right side up. When the operator picks up the stamp he must look for this mark.

My invention contemplates the application to a stamp of this general character of means which will cause the stamp to roll over on a flat surface and will create a condition of unstable equilibrium in the stamp until it finally adjusts itself in such a position of rest that when picked up by the operator it will be in the proper position for use. My invention further contemplates the association with such a device of a means for indicating the character of the reading matter upon the stamp.

The principal object of my invention therefore is to provide a rubber stamp which will, when placed upon a flat surface, be in a condition of unstable equilibrium except when it is in the proper position to be grasped for use by the operator. Another object of my invention is to provide a means of this character whereby the stamp may be suspended from a hook or nail with the axis of the handle horizontal, and with which there may be associated conveniently observable means indicating the character of the reading matter upon the stamp.

With these objects in view my invention includes the novel elements and the combinations and arrangements of elements illustrated in a more or less typical way in the accompanying drawings in which—

Fig. 1 is a top view of a stamp with one species of my self-righting means attached thereto;

Fig. 2 is a view similar to Fig. 1 showing the preferred form of my invention;

Fig. 3 is a side view of Fig. 2 showing

how my stamp may be suspended from a nail;

Fig. 4 illustrates a side view of a stamp in a condition of unstable equilibrium upon a flat surface;

Fig. 5 is a side view of Fig. 4 showing the stamp as it begins to roll into a position of stable equilibrium such as illustrated in Figs. 1 and 2;

Fig. 6 illustrates how my device may be made an integral part of the frame of an ordinary "dating stamp"; and

Fig. 7 shows a slight modification of my invention adapted for attachment to a stamp.

Referring to the drawings, 1 represents the handle of an ordinary stamp, 2 is the wood body portion of the stamp into which the handle is normally glued, and 3 represents the rubber cushion upon which the type are ordinarily cemented or it may represent the type themselves.

My invention, in part, comprises the application to a stamp of this character of a thin disk, 4, of comparatively rigid material such as thin metal, wood, celluloid or the like. The important feature of this disk is the curvilinear edge, 5, which is preferably, but not necessarily, circular in form and which lies in a plane normal to the axis of the handle. This curvilinear edge should extend entirely about three of the four sides of the body portion of the stamp. The plane of the curvilinear edge, 5, preferably passes through the center of gravity, 6, of the assembly so that the stamp when hung from a nail, 7, passing through the hole, 27, as shown in Fig. 3, will normally rest with the axis of the handle horizontal. Where the plane of the curvilinear edge, 5, cannot be conveniently located in this position I prefer that it should be normal to the axis of the handle at a point intermediate the center of the gravity of the assembly and the end remote from the handle.

When the device has been assembled so that these relations exist between the various parts, the stamp will, if dropped upon a flat surface, first assume a position such as shown in Fig. 4, and the weight of the stamp will be supported merely upon two points, to wit, the point, 8, where the handle is tangent to the surface, 9, and the point, 10, where the curvilinear edge, 5, is tangent to the supporting surface. The weight of the as-

sembly acts downwardly through the center of gravity in the direction of the arrows, 11 in Fig. 3, 12 in Fig. 4 and 13 in Fig. 5. Unless the device is precisely on "dead center" the vertical force of gravity as represented by the arrows 11, 12 and 13 will be on one side or the other of the line joining the points of tangency, 8 and 10, and will thus tend to cause the stamp to rotate in the direction of the arrow, 14, (see Fig. 5), until it rolls completely over and lies upon the flat face, 15, in stable equilibrium.

The preferred form of my invention is shown in Fig. 2. The curvilinear edge, 5, 15 is a perfect circle drawn from the center, 16, and passing through the corners, 17 and 18, of the body of the stamp. The center, 16, of this circle is somewhat removed from the axis, 19, of the handle.

20 Where it is desirable to reduce the size of the disk, 4, the curvilinear edge, 5, may be a circle described with a center upon the axis of the handle as shown in Fig. 1. In either case it may be desirable to provide the 25 curvilinear edge, 5, midway between its extremities, with an abrupt projection or point, as shown at 20 in Fig. 1, so that it will be quite impossible for the stamp to come to rest on "dead center," in the position shown 30 in Fig. 4.

In its preferred form the disk may be attached to the body portion of the stamp by means of screws, 21 and 22, or by any other convenient means.

35 23 represents a piece of clear celluloid which is secured to the body portion of the stamp by the screws, 21 and 22, and which is held in close engagement with the disk, 4, by means of the over-turned clips, 24 and 25, 40 cut out of the disk and bent over the edges of the celluloid. Beneath the celluloid, 23, there may be placed a piece of paper, 26, bearing a legend indicating the character of the stamp.

45 Where it is desired to apply my invention to an ordinary dating stamp having a metal frame, it is possible to form the disk and frame as an integral unit as illustrated in Fig. 6. If it is desired to attach the device 50 to a metal frame stamp it may be made somewhat as shown in Fig. 7, and secured to the frame by means of screws.

The best results, I believe, are attained by 55 making the curvilinear edge, 5, a segment of a circle which subtends a central angle, A, somewhat in excess of 180 degrees. However, this curve may be somewhat modified provided the device will be in a condition of unstable equilibrium when supported at 60 any point thereon and on the handle, as shown in Fig. 4. The device is intended to, and must roll over to a position of stable equilibrium without any hesitation, and with this end in view both the edge, 5, and the 65 line of rolling support about the handle

should be smooth curves and preferably circles.

I am aware that it has been proposed by others, notably Stevenson in his U. S. Patent N°. 1,446,671, to form a self-righting stamp 70 by means of a surrounding curved element or arm of wire or the like. Such devices are difficult to form as compared with my disk which may be cut with a simple die, and wire-like arms are easily deformed and 75 otherwise damaged, whereas my disk is practically indestructible. Furthermore my disk is adapted to form a legend carrier of sufficient size to bear the complete imprint of the 80 stamp.

While I have described my invention in its preferred form, it is to be understood that the words which I have used are words of description rather than words of limitation, and that changes within the purview of the 85 appended claims may be made without departing from the true scope and spirit of my invention in its broadest aspects.

What I claim is—

1. An article of manufacture adapted for 90 attachment to a stamp or the like to make it self-righting, comprising a disk of substantially rigid material having a curvilinear edge approximating a segment of a circle and subtending a central angle in excess of 180 degrees; the edge, midway between the extremities thereof, being provided with an abrupt projection.

2. In a stamp of the character described 100 having a handle thereon, a hanger comprising a perforated, segmental disk of rigid material secured to said stamp at right angles to the axis of said handle and having the plane thereof passing substantially through the center of gravity of the whole; 105 whereby said stamp may be suspended in stable equilibrium with the axis of the handle horizontal.

3. In a stamp having a handle thereon, a 110 hanger comprising a perforated plate secured thereto and adapted to hold said stamp suspended from a point of support with the axis of the handle substantially horizontal; and a transparent element secured in contact with said plate on the side 115 toward the handle adapted to permit a legend indicating the character of the stamp to be read therethrough.

4. In a rubber stamp or the like provided 120 with a handle and a body, a plate secured to said stamp and forming a legend carrier offset from the side of said body and lying substantially parallel to the face of the stamp.

5. The combination with a stamp comprising 125 a body portion and a handle, of a rigid disk secured thereto at right angles to the axis of the handle and having its plane passing substantially through the center of gravity of the whole; said disk 130

being provided with a curvilinear edge forming, with said handle, an unstable support for the whole, adapting said stamp to roll about on a flat surface, to a predetermined position of stable equilibrium.

6. The combination with a stamp comprising a body portion and a handle, of a rigid disk secured to said stamp intermediate the handle and body portion; said disk being provided, near its edge, with a centrally disposed opening adapted to receive a hook for hanging the stamp; and said

edge being curvilinear and forming, with said handle, an unstable support for the whole, adapting said stamp to roll about on a flat surface to a predetermined position of stable equilibrium.

7. The structure as defined in claim 5 in which the curvilinear edge is provided with a centrally disposed abrupt projection. 20

8. The structure as defined in claim 6 in which the curvilinear edge is provided with a centrally disposed abrupt projection.

FRANK BOGASKIE.
